UNITED STATES PATENT OFFICE

172,025

COMBINED PENCIL, PENCIL HOLDER, AND PAPER CUTTER

Robert Hopstein, Brooklyn, N. Y.

Application February 4, 1953, Serial No. 23,443

Term of patent 14 years

(Cl. D74—1)

To all whom it may concern:

Be it known that Robert Hopstein, a citizen of the United States of America, residing in Brooklyn, in the county of Kings and State of New York, has invented a new, original, and ornamental Design for a Combined Pencil, Pencil Holder, and Paper Cutter, of which the following is a specification, reference being had to the accompanying drawing forming a part hereof.

Fig. 1 is a front elevational view of a combined pencil, pencil holder, and paper cutter, showing my new design,

Fig. 2 is a rear elevational view,

Fig. 3 is a side elevational view thereof as it appears in disassembled position, and

Fig. 4 is a sectional view thereof taken on the line 4—4 of Fig. 1.

I claim:

The ornamental design for a combined pencil, pencil holder, and paper cutter, as shown.
